UNITED STATES PATENT OFFICE.

FRANK T. WATSON, OF FULTON, NEW YORK, ASSIGNOR TO THE FULTON PULLEY COMPANY, OF SAME PLACE.

DESIGN FOR A SHAFT-SUPPORTER.

SPECIFICATION forming part of Design No. 30,034, dated January 17, 1899.

Application filed October 27, 1898. Serial No. 894,749. Term of patent 3*1* years.

To all whom it may concern:

Be it known that I, FRANK T. WATSON, a citizen of the United States, residing at Fulton, in the county of Oswego and State of New York, have invented and produced a new and original Design for a Shaft-Supporter, of which the following is a specification, reference being had to the accompanying drawing, forming part thereof.

10 In said drawing the single figure shows my shaft-supporter in side elevation, which sufficiently illustrates its peculiar configuration.

The leading feature of this design lies in its general contour, that is substantially the form 15 of the letter L, the two arms being formed, respectively, as here shown, plano-convex or concavo-convex.

In the drawing, 1 indicates the plano-convex arm, having the plain side 2 and the convex or slightly-swelling side 3.

20 4 indicates the concavo-convex arm, having a convex side 5, a parallel concave side 6, and the notched end 7. Between these two arms is arranged the diagonal bar 8.

Having described my invention, what I claim as new, and desire to secure by Letters Patent, is—

The design for a shaft-supporter, as herein shown and described.

FRANK T. WATSON.
